UNITED STATES PATENT OFFICE.

WILLIAM C. PRESSING, OF NORWALK, OHIO.

DESIGN FOR A BOTTLE.

No. 38,430.

Specification for Design.

Patented Jan. 29, 1907.

Application filed December 26, 1906. Serial No. 349,588. Term of patent 14 years.

To all whom it may concern:

Be it known that I, WILLIAM C. PRESSING, a citizen of the United States, residing at Norwalk, in the county of Huron and State of Ohio, have invented a new, original, and ornamental Design for a Bottle, of which the following is a specification, reference being had to the accompanying drawings, forming part thereof.

In said drawings, Figure 1 is a side eleva-

tion of a bottle, showing my new design. Fig. 2 is an edge view. Fig. 3 is a bottom plan view.

I claim—

The ornamental design for a bottle, as shown.

WILLIAM C. PRESSING.
